UNITED STATES PATENT OFFICE.

HENRY SATTLER, OF SWISS, MISSOURI.

HILLSIDE-PLOW.

SPECIFICATION forming part of Letters Patent No. 242,697, dated June 7, 1881.

Application filed April 14, 1881. (Model.)

To all whom it may concern:

Be it known that I, HENRY SATTLER, of Swiss, in the county of Gasconade and State of Missouri, have invented certain new and useful Improvements in Hillside-Plows; and I do hereby declare the following to be a full, clear, and exact description of the invention, such as will enable others skilled in the art to which it pertains to make and use it, reference being had to the accompanying drawings, which form part of this specification.

My invention relates to an improvement in side-hill plows; and it consists in the arrangement and combination of parts, which will be more fully described hereinafter, whereby a cheap, simple, and effective plow is produced.

Figure 1 is a side elevation of my invention. Figs. 2, 3, 4, 5, 6, 7 are detail views of different parts of the plow.

20 A represents the beam of the plow, which may be made of the curved form shown, and which is wider along its lower edge than at any other point. The rear end of this beam is curved backward to the center of the double 25 mold-board C, and through the end of this beam and the double mold-board is passed the pivotal rod D. In between the two landsides of the double mold-board is secured a brace, E, of the shape shown, and which is provided 30 with perforated ears or projections, through which fastening-bolts are passed for the purpose of securing it in position. This brace closes up to a considerable extent the space between the two landsides of the double mold- 35 board, and owing to its shape the brace will easily move along past the earth without clogging up. The rear end of the pivotal rod is journaled in the lower end of the hanger F, which is secured to the lower part of the brace 40 or support G. This brace or support for the handles has secured to its front side a brace, H, which is of the shape shown, and which is provided with a projection, I, below its center. Below this projection the brace is inclined backward, and has its lower end fastened to the 45 hanger, so as to give it additional strength and support. The brace G has secured to each side of its lower end a flat plate, J, which extends forward, and has its front end secured to the 50 rear end of the beam A. The projection I fits in between these two parts, and through the

two plates and projection is passed a suitable clamping-bolt, as shown, for the purpose of bracing the parts rigidly together. In between these two plates is pivoted the double catch L, 55 which consists of the two prongs M, for catching over the top of each one of the landsides as the mold-boards are turned up into position, and thus keep the mold-boards in place. On the under side of the center of this catch is 60 formed the flange N, which projects down between the two plates and receives the pivoting-bolt, upon which it turns. On the rear end of the catch are formed the two shoulders O, 65 which catch against the tops of the two plates, and thus prevent the catch from being moved too far back by means of its operating-rod P, which is loosely attached to a projection, Q, upon its top. This catch, being made heaviest upon its front end, drops forward of its own 70 weight whenever this operating-rod is released, so as to be perfectly automatic in its action, without the help of any other device.

The front ends of the two handles are inclosed upon three sides by means of the sockets R, 75 and are then bolted to the beam A. These sockets are secured to the handles in any suitable manner at their upper ends, and serve to prevent the handles from being broken, split, or injured, as they are always liable to be when 80 left unprotected.

Passed over the front end of the beam A is the supporting-slide T, to which the revolving toothed cutter V is swiveled. This slide is provided with a set-screw, by means of which 85 it is secured to the beam A, and by loosening this screw the cutter can be moved backward, so as to run back over the top of the share, or can be moved forward to the front end of the beam, so as not to run over the share at all. 90 This support is made hollow in its lower end, and into which the upper end, U, of the swiveled bearing of the cutter extends. In order to secure the upper end of this bearing in the sliding support, two holes are made through 95 the opposite sides of this sliding support, and then clamped around the support. Just opposite these holes are the two pronged catches W. Each one of these catches W is made semicircular in shape, and has the projection X at its center to pass through one of the holes in the side of the sliding support and catch in the groove 100.

- made in the upper end of the bearing of the journal. The two ends of these two catches are clamped together by means of nuts and bolts, so as to hold them more securely in position. There may be only one or a series of grooves made in the upper end of the support for the wheel, whereby the wheel can be made to run high above the plow-point or close down to it.
- 10 The rolling cutter is provided with sharp pointed teeth, and the edge of the cutter is sharpened in between the teeth, so as to make the cutter cut more easily, and to prevent it from becoming dull as soon as it would if only the sharp edge were formed. The center of this cutter has a suitable bearing riveted or otherwise secured to each of its sides, so that when the bearing has become worn out another one can be readily supplied.
- 15 20 I am aware that a rolling colter has been swiveled in a box and the box made adjustable upon the beam, and this I disclaim.

Having thus described my invention, I claim—

1. The combination of the support G, and the brace H, secured to its front side and provided with the projection I, with the plates J, extending forward and having their front ends fastened to the beam A, substantially as shown.

2. The combination of the supporting-slide 30 T, having its lower end made hollow and provided with holes upon opposite sides, with the curved end of the support for the cutter, and the two clamps W, provided with projections for passing through the holes in the sides of 35 the sliding support, substantially as specified.

In testimony whereof I affix my signature in presence of two witnesses.

HENRY SATTLER.
